UNITED STATES PATENT OFFICE.

ALBERT C. EARHART, OF CLEVELAND, OHIO.

DOORCHECK OR STOP.

Application filed January 6, 1928. Serial No. 244,796.

This invention relates generally to a door check or stop and more particularly to one intended for use upon the doors of automobiles and similar structures.

5 At the present time when automobile bodies and doors are made entirely of metal, the convenient positioning of the door check has been a problem and this invention is devised to solve that problem, being especially 10 adapted to the all metal door in connection with an all metal frame of an automobile.

Broadly the invention consists in aperturing the leaves of the door hinge connecting a rod to one leaf of the hinge, passing said 15 rod through the other leaves and providing said rod with a yieldable stop to limit the outward movement of the door and to cushion the checking action.

The invention consists also in certain 20 tails hereinafter fully described and pointed out in the claim.

In the drawings forming a part of this specification, Fig. 1 is a horizontal sectional view, partly in plan showing a part of the automobile frame, a part of the door frame, the hinge and swinging check rod; Fig. 2 is a vertical sectional view with the rod and cushion in elevation and Fig. 3 is an end view of the cushion.

30 Referring to the drawings, 10 indicates a portion of the all metal side of the automobile body and 11 a portion of the all metal door. 12 is the leaf of the hinge which is connected to the body post and 13 is the leaf 35 connected to the door; these leaves being pivotally connected together at 14.

Each leaf of the hinge is slotted horizontally as shown at 12^a and 13^a respectively and working in these slots is a flat rod 15. One 40 end of this rod is pivoted to a plate 16, fastened upon the inner side of the door and formed with a loop 16^a on which the end of the rod 15 is pivoted as shown at 15^a.

Upon the opposite end of the rod, there is 45 arranged a yieldable stop 17 of rubber or any suitable material and this stop contacts with a slotted plate 18, arranged upon the inter-

rior face of the body member, and in practice I prefer to interpose a piece 19 of leather, fiber or any other suitable material between 50 the metal plate 18, and the interior of the body member.

It will be noted that the same bolts or screws which are employed to secure the leaves of the hinge also serve for securing the 55 pivot plate 16, and the stop receiving plate 18.

In practice I prefer to recess the opposing faces of the body and door to receive the 60 leaves of the hinge but this may not be necessary.

The free end of the rod 15 is notched and has washers fastened thereon, as shown, described and claimed in my application filed 65 August 4, 1927, Serial No. 210,480.

By slotting the leaves of the hinge and 70 passing the stop rod through the leaves, an exceedingly cheap, simple and convenient arrangement is provided and particularly adapted for use upon all metal bodies and doors.

Having thus described my invention, what I claim is:

In combination with the body and a hinged door member of an automobile in which the body, door member and leaves of one of the 75 hinges thereof have aligned slots extending in the plane in which one of said leaves swings, a sheet metal bracket secured to the inner side of one of said members having spaced ear portions, a flat rigid bar pivoted 80 at one end between said ear portions and extending through the slots in said leaves, body and door members to swing in the plane of said bar, said bar having spaced recesses at 85 its opposite end, a yielding stop cushion arranged on the free end of said bar, and adjustable stop means on the free end of said bar against which said cushion abuts, said means including a member having a portion to engage in said recesses.

In testimony whereof, I hereunto affix my 90 signature.

ALBERT C. EARHART.
